JOINTED CONDENSER WITH SEVERAL DELIVERY TUBES

Filed July 8, 1938.

UNITED STATES PATENT OFFICE

2,232,394

JOINTED CONDENSER WITH SEVERAL
DELIVERY TUBES

Tsu-Liang Ko, Kaifeng, China

Application July 8, 1938, Serial No. 218,143

1 Claim. (Cl. 257—42)

This invention relates to a condensing apparatus.

The principal object of this invention relates to the provision of a plurality of vertical condenser units connected together in series and arranged within a jacket containing a circulating cooling medium such as water, each condenser unit having a delivery tube extending outwardly therefrom and through the wall of the jacket, and with the lowermost condenser unit connected to a heated vessel arranged externally and remote from the jacket and containing a liquid compound which is to be broken up into its several constituent parts by a distilling process.

Other objects of this invention relate to the provision of a condensing apparatus which shall be efficient in operation, of relatively few and simple parts, cheap to manufacture, easily applied for the purpose intended and simple to operate.

With these and other objects in view as will become hereinafter apparent from a detailed description of the invention, reference is had to the accompanying drawing, wherein—

Figure 1 is an elevational diagrammatic view of one form of condensing structure arranged within a closed jacket.

Figure 2 is a like elevational diagrammatic view of a modified form of condensing structure.

Figure 3 is also a like elevational diagrammatic view of a still further modified form of condensing structure.

Referring to the drawing in detail, and first to the form of invention shown in Figure 1, 10 indicates a cylindrical jacket of any suitable material and size closed at each end. At the upper end 11 of the jacket there is provided an inlet nipple 12 to which may be connected a hose or pipe (not shown) from a source of cooling water supply, and at the lower end 13 there is provided an outlet nipple 14 for like connection to a hose or pipe (not shown) through which the water is discharged.

Arranged within the jacket 10 are a plurality of condenser units 15, 15a and 15b arranged vertically one above the other. All of the condenser units are of the same shape and size. Thus the condenser unit 15 comprises a container portion 15, provided at its top with a vertical central feed tube 16 and at its base with a downwardly and outwardly inclined delivery tube 17. In a like manner the condenser units 15a and 15b are provided respectively with like feed tubes 16a, 16b and delivery tubes 17a, 17b.

The condenser units are interconnected by the feed tube 16 which extends within the condenser unit 15a through the bottom thereof and is attached thereto in liquid tight engagement in any desired manner. In a like manner the feed tube 16a extends into the condenser unit 15b and is secured thereto in the same manner. The exhaust feed tube 16b projects outwardly of the top 11 of the jacket 10 and is fixed thereto in liquid tight engagement, said tube 16b being either open to the atmosphere or is adapted to be connected to an exhaust hose or pipe not shown. The delivery tubes 17, 17a and 17b project outwardly of the wall of the jacket 10 as shown in a downwardly inclined direction each being adapted to have attached thereto a suitable hose for conducting the condensed liquid to a proper receptacle or receiver (not shown).

Extending upwardly through the bottom end wall 13 of the jacket 10 and into the lower condenser unit 15 is a primary feed tube 18 communicating with a flask or container 19 in which is adapted to be placed any desired liquid compound that is to be broken up into its constituent liquids by a fractional distillation. Thus by the application of heat or a flame to the flask 19 the liquid constituents of the compound therein are vaporized at different temperatures depending upon the boiling point of the various liquids that go to make up the compound. Accordingly the liquid constituent that has the lowest boiling point will vaporize first and being of less density will rise to the uppermost condenser unit 15b where it will be condensed due to the circulation of the cooling water through the jacket, the condensed liquid constituent thereupon flowing out of the delivery tube 17b. In this fashion the other liquid constituents are boiled off or vaporized at higher temperatures and will be condensed in the other condenser units 15a and 15 for collection at the delivery tubes 17a and 17. As the various vapors are condensed in their respective condenser units, the vapors that rise to the higher condenser units are washed in their passage through the body of condensed liquid constituents in said lower condenser units, thus insuring a more perfect separation of the constituent liquids. It is to be understood that any desired number of such condenser units may be assembled within a jacket as may be found necessary. Vapors not desired for condensation having very low boiling points may be exhausted by passing out of the uppermost feed tube 16b. It is to be further understood that the temperature of the cooling water

may be also controlled and varied in the manner well known, to control the condensation of the constituent liquids desired.

In Figure 2 there is shown a modified arrangement of condenser units and water jacket. In this case the condenser units 25, 25a and 25b are arranged vertically one above the other and adjacent one side of the water jacket 20. Connecting the condenser units 25 and 25a is a U-shaped feed tube 26, and connecting the condenser units 25a and 25b is a like U-shaped feed tube 26a. An exhaust tube 26b communicates the upper condenser unit 25b with the atmosphere or a collecting chamber (not shown). Extending through the base of the jacket 20 and into the lower condenser unit 25 is a feed tube 28, the lower end of which is to be connected to a flask or container such as 19, see Figure 1. Each of the condenser units 25, 25a and 25b are respectively provided with downwardly inclined delivery tubes 27, 27a and 27b that project outwardly of the jacket 20. The water jacket 20 is a container of any desired shape and size open at the top and filled with water which may be changed, circulated or agitated in any desired manner. The arrangement shown in Figure 2 operates in the same manner, as that described above with reference to Figure 1.

The modified arrangement of condenser units and water jacket shown in Figure 3 is similar to that of Figure 2 with this distinction that the feed tubes 36, 36a and 36b are looped in form so as to provide feed tubes of greater length. The condenser units 35, 35a and 35b, delivery tubes 37, 37a and 37b, feed tube 38 and water jacket 30 are similar to that shown in Figure 2.

Having thus described my invention I claim as new, and desire to secure by Letters Patent:

A multiple condenser device comprising a plurality of like elongated single container condenser units each provided with a cup-shaped bottom and top and arranged one above the other in series relation, an elongated jacket containing a cooling medium housing said condenser units, said jacket being of such a size as to provide a substantial space between the walls thereof and said condenser units axially disposed therewithin, a feed tube connecting the top of one condenser unit with the bottom of the next adjacent condenser unit, a primary feed tube extending outwardly of said jacket and connected to the bottom of the lowermost condenser unit, an exhaust feed tube connected with the top of the uppermost condenser unit and extending outwardly of said jacket, said feed tubes, primary feed tube and exhaust feed tube being coaxially disposed with respect to each other and each of said feed tubes projecting axially into its associated condenser unit a substantial distance above the cup-shaped end thereof, and a delivery tube for each condenser unit connected to the cup-shaped bottom of each substantially at its lowermost point, said delivery tubes being inclined downwardly and extending outwardly from the same side of the jacket, said jacket being closed at its top and bottom, an inlet pipe provided at the top of said jacket and an outlet pipe provided at the bottom of said jacket in diagonally opposed relation thereto whereby to provide a constant circulation of cooling medium through said jacket.
